Inventor:

UNITED STATES PATENT OFFICE.

LUTHER C. THOMPSON, OF WASHINGTON, DISTRICT OF COLUMBIA.

MECHANICAL MOVEMENT.

1,238,361.

Specification of Letters Patent. Patented Aug. 28, 1917.

Application filed September 13, 1916. Serial No. 119,949.

To all whom it may concern:

Be it known that I, LUTHER C. THOMPSON, a citizen of the United States, and a resident of the city of Washington, in the District of Columbia, have invented a new and Improved Mechanical Movement for the Transmission of Power, the following of which is a full, clear, and exact description of the invention, that will enable those skilled in the art to make and use the same, reference being had to the accompanying drawings and the figures and letters of reference thereof, that form a part of this specification.

15 The object of this my invention is to provide an improved mechanical movement in duplex form that will transmit a generated power to the driving shaft.

This my invention relates to a reversible mechanical movement in connection with a driving shaft having a speed wheel and an eccentric rigidly keyed thereto, and an eccentric ring journaled upon the eccentric, an arm extending from the eccentric ring to the reciprocating guide block, and the said arm being journaled with the reciprocating block. The journaled connections forming a part of said block, and extending through the slotted base supports, and having a journaled connection with the operating lever below the base support.

The reciprocating racks being provided with parallel guides. The actions of the racks and pistons are governed by the reversible movements of the cog wheel, that is timed by the eccentric.

Figure 1 is a longitudinal bottom view of the bed plate, showing the timing levers, and their connecting supports, Fig. 2 is a longitudinal top plan view, Fig. 3 is a detached front elevation of the clutch mechanism, Fig. 4 is a top elevation of the rack 11 detached, Fig. 5 is an end elevation of the motor cylinders connected with the bed plate, and showing the incased exhaust ports. Like letters and figures denote like parts wherever they may occur.

The shaft I is journaled in the boxes L and M that forms a part of the bed plate 19, the speed wheel K' is rigidly keyed to the shaft I at I', the ratchet case R' and the ratchet case R being rigidly keyed to the drive shaft I, the eccentric 26 is rigidly keyed to the drive shaft I, the eccentric ring

8' is provided with an arm 27, the end 55 thereof being connected with the reciprocating guide block X by the journal 8, the guide block X reciprocates in the guide slot 39, the journal W forms a part of the guide block X and is connected with the end of 60 lever 1, the opposite end of lever 1 is hinged at 28' with the link N', the link N' is journaled to the plate 19 at 28, the lever 2 is journaled to the bed plate at 3', the opposite end is journaled to the connecting rod 65 4 at 4', the connecting rod 4 is journaled to the rack 11 at 5, and operates in the slotted opening 16, the connecting bar 25 is journaled to the lever 1 at 1', and journaled to the lever 2 at 2'. The revolving movements 70 of shaft I and the eccentric 26 operates the levers 1 and 2 and the rack 11, the cogs in the sides thereof interlocking with the cog-wheel 15 that forms a part of the timing mechanism. The reciprocating rack 12 is 75 provided with cogs C at the side thereof that interlock with the cogs of the reversible timing gear 15. The timing gear 15 is journaled in position to the bed plate 19 by the shaft 17, and supported by the bracket 80 18. The rack 11 is provided with cogs D' that interlock with the drive wheel S. The reciprocating rack 12 is provided with cogs D that interlock with the cogs of the drive wheel T. The drive wheel S having an ex- 85 tended hub and a flange O that forms a part thereof, and ratchet pawls 21 and 21 that are pivoted to the flange O by the pins 20 and 20. The flange O and the pawls 21 are inserted in the ratchet case R. The 90 driving gear S being loosely journaled on the shaft I and having a reversed motion in union with the reciprocating movements of the rack 11. The drive wheel T is loosely journaled upon the shaft I, and is connected 95 to the shaft I by a one-way ratchet clutch R, similar to the ratchet clutch R'. The rack 11 and rack 12 are retained in the parallel position with the cylinders 6' and cylinders 6 by the guide plates 14, 14 and 13. 100 The cylinder pistons A and A' are rigidly bolted to the racks 11 and 12 at B B, see Fig. 4. The application of power in the cylinder 6' or 6 may be generated by explosive vapor or steam as preferred. The 105 valves are incased in the chambers H H, that form a part of the cylinder heads, but may be constructed in various ways without

departing from the spirit of my invention. An explosion of vapor in the cylinders 6 affords a forward movement of the pistons A and the rack 11, revolving the power 5 wheel S, and locking the clutch pawls 21 in the ratchet connections that form a part of the case R. An explosion of vapor in the cylinders 6 forces the pistons A and the rack 12 in a forward movement that inter- 10 lock the clutch mechanism in the case R, and transmitting the power to the shaft I, and revolving the timing gear 5', and reciprocating the rack 11 that is released by the pawls 21, 21. The rotary impulse given 15 to the speed wheel K' is not subjected to back pressure on the pistons A and A.

Power is imparted to the rack bars by the pistons which are operated alternately, thus driving shaft I through the gears and 20 ratchet clutches, the ratchet clutches overrunning on the return stroke. The cog wheel 15 serves the purpose of returning the rack bars and pistons after each downward stroke as is plainly evident from the drawing. The eccentric in coöperation with the 25 levers 1 and 3 and links connected thereto limits the movement of the rack bars.

Having thus described my invention, what I claim as new in a mechanical movement

for the transmission of motor power, and 30 desire to secure by Letters Patent is:

1. In a device of the class described, a plurality of driving reciprocating members, a driven shaft, mechanism connecting said reciprocating members and said driven 35 shaft, for operating said shaft, an eccentric mounted on said shaft, a plurality of connected and pivotally mounted levers, one of said levers being connected to said eccentric, the other of said levers being connected 40 to one of said reciprocating members, and a gear in operative engagement with both of said reciprocating members.

2. In a device of the class described, a plurality of reciprocating driving members, 45 a driven shaft, mechanism connecting said driving members and said shaft for operating the latter, mechanism connecting said driven shaft and one of said driving members for limiting the throw of said driving members, and a gear in operative engagement 50 with said driving members, for the purpose described and set forth.

LUTHER C. THOMPSON.
